UNITED STATES PATENT OFFICE.

WILLIAM G. KENDALL, OF NEWARK, NEW JERSEY.

VANITY CASE.

Application filed January 4, 1923. Serial No. 610,615.

To all whom it may concern:

Be it known that I, WILLIAM G. KENDALL, a citizen of the United States, and a resident of Newark, in the county of Essex and State of New Jersey, have invented a new and Improved Vanity Case, of which the following is a full, clear, and exact description.

The present invention relates to new and useful improvements in vanity cases, and it comprises an improvement over the structure shown in my prior United States Letters Patent No. 1,229,286, granted June 12, 1917.

It is one of the objects of the present invention to provide a small compact vanity case adapted to carry a plurality of cosmetics, such as face powder and rouge, in the form of compacts.

It is a further object of the invention to mount these cosmetic compacts that either may be positioned in such a manner that access thereto may be readily obtained.

It is a further object of the invention to provide a new and improved lid structure embodying a new and improved means for retaining a mirror in position therein.

With the above and other objects in view, reference is had to the accompanying drawings, in which—

Figure 1 is a rear view of a vanity case constructed in accordance with the present invention, the vanity case being shown in closed position;

Fig. 2 is a longitudinal sectional view thereof taken on the line 2—2 of Fig. 1;

Fig. 3 is a plan view of the vanity case shown in partially open position;

Fig. 4 is a similar view shown in completely open position;

Fig. 5 is an enlarged detail sectional view taken on the line 5—5 of Fig. 1;

Fig. 6 is an enlarged detail sectional view showing the vanity case in the completely open position.

Referring more particularly to the drawings, the reference character 10 designates the body of the vanity case, and 11 designates the cover thereof. This cover is hinged to the body 10 of the vanity case, by means of a hinge 12 which is carried by the rear end of the body. A plate 13 is hingedly connected to the front wall of the body 10 of the vanity case in such a manner that it is adapted to be received within the vanity

case or swung outwardly thereof as shown in Fig. 4. This plate has two hinge members 14 comprising bent ears 15, said hinge members passing through openings 16 in the front wall 17 of the body 10 of the vanity case. Between the hinge members 15 of the plate 13, there is a thumb-piece 18 which serves as the operating means by which the plate 13 is moved to the position shown in Fig. 4.

The reference character 19 designates a rouge compact, and the reference character 20 designates a powder compact, these two compacts being secured in position on the plate 13 by means of oppositely-disposed ears 21, which ears are struck upwardly and adapted to engage the metallic container of the compacts. By this means the cosmetic compacts are secured to the opposite faces of the plate 13.

The cover 11 is provided with an inwardly disposed bead 25, said bead being formed by crimping the cover 11 inwardly as designated by the reference character 26.

The reference character 27 designates a mirror, which is adapted to be secured within the cover 11, and said mirror is positioned in such a manner as to engage angularly disposed faces 28 of the cover 11. After the mirror has been so positioned, a bezel 29 is placed in the cover, said bezel being received behind the bead 25 in such a manner as to secure the mirror 27 against accidental displacement in the cover. This bezel 29 is formed of resilient material and serves to maintain the mirror in contact with the angular faces 28.

The device operates in the following manner:

The vanity case being opened by raising the cover 11, the powder compact 20 is readily accessible. If, however, it is desired to use the rouge compact, the finger-piece 18 is engaged grasped, preferably by the thumb, and the plate 13 is rocked about its hinges 14 to the position shown in Figs 4 and 6. When the plate 13 is in this position, the rouge compact will be exposed for use and the member 18 by reason of its engagement with the outer face of the front wall of the vanity case, as illustrated in Fig. 6, serves to support the plate 13 in the position in which the rouge compact is exposed.

Should the mirror become broken, or it is desired to remove the same, it is only

necessary to spring the bezel 29 from behind the bead 25, when the mirror will be free for removal.

From the foregoing it is apparent that the present invention provides a new and improved vanity case in which a plurality of cosmetics may be carried within a relatively small article of this character. Furthermore, by the construction of the vanity case, either of the cosmetics may be exposed for use.

What is claimed is:

1. In a cover construction for vanity cases, a cover member having angular faces adapted to form a support for a mirror or the like, a bead formed in said cover and

inwardly disposed with respect thereto, and a bezel of resilient metal adapted to be received behind said bead and exert sufficient pressure on the mirror to retain the same in contact with the aforesaid angular faces.

2. A cover construction for vanity cases comprising a bead formed on said cover, said bead being disposed inwardly thereof, a mirror adapted to be received within the cover on the inner face thereof, and a bezel of resilient material adapted to engage behind said bead and exert pressure upon the mirror to maintain the same in engagement with the walls of the cover.

WILLIAM G. KENDALL.
